UNITED STATES PATENT OFFICE.

ROBERT DEMING, OF CLEVELAND, OHIO.

BOOT-DRYING APPARATUS.

Application filed May 4, 1922. Serial No. 558,339.

To all whom it may concern:

Be it known that I, ROBERT DEMING, a citizen of the United States, resident of Cleveland, county of Cuyahoga, and State 5 of Ohio, have invented new and useful Improvements in Boot-Drying Apparatus, of which the following is a specification, the principle of the invention being herein explained and the best mode in which I have 10 contemplated applying that principle, so as to distinguish it from other inventions.

My invention relates to boot drying apparatus, its object being to provide a device of this character which may be easily manufactured, simple in construction and efficient 15 in its operation. The said invention consists of means hereinafter fully described and particularly set forth in the claims.

In the annexed drawings:

20 Fig. 1 represents a front elevation of an apparatus embodying my invention.

Fig. 2 represents a side elevation thereof.

Fig. 3 represents, upon an enlarged scale, a fragmentary axial section.

25 Fig. 4 represents a longitudinal section of the device when knocked down and assembled for transportation.

Fig. 5 represents a prospective view of the device assembled.

30 Fig. 6 represents a section taken on line VI—VI, Fig. 4.

Fig. 7 represents a side elevation of a modified form.

35 Fig. 8 represents, upon an enlarged scale, a fragmentary axial section of the modified form.

Fig. 9 represents an elevation of the lower end of one of the tubes forming a part of the device with the cap removed; and

40 Fig. 10 represents a section taken on line IX—IX, Fig. 8.

Referring first to the form of heater shown in Fig. 1, the device comprises a base 1 and two tubes 2—2, each consisting of two 45 telescoping parts. The base consists of two similar parts 3 and 4 which are complementary to each other, hinged along the one edge 5 and when closed, as shown in Fig. 5, forming a rectangular receptacle. The ends 50 of the receptacle are provided with hooks 6 and eyes 7 by means of which the two parts may be secured in their closed position as shown in Fig. 5 and are secured in their open position as shown in Fig. 2. Secured

upon the inner surface of the side 8 of one 55 of the two parts are two pairs of lugs 9—9, adapted to enter apertures 10—10, formed in the lower sections of the tubes 2—2, whereby these tubes may be detachably mounted and supported as shown.

When the receptacle is opened and locked it forms a base for supporting tubes 2 as shown in Fig. 2. When it is closed it is adapted to receive and hold the sections of the tubes as shown in Fig. 6.

The upper section of each tube is provided with the air outlets 11 and the lower sections with the air inlets 12. The bottom of the lower section is closed by a cap 13 removably secured by studs 14 engaging bayonet slots 16, Fig. 9. To the inner face of the cap is secured a socket 17 in which a heating element such as a candle may be mounted. Assuming the above described parts to be assembled as shown in Figs. 4, 5 and 6, when it is desired to use same the hooks 6 are detached and the two parts opened to assume the position shown in Fig. 2, whereupon the hooks are caused to engage the eyes and lock the parts in such open position. The tubes are then assembled and attached to the lugs 9, the candles first having been lighted.

The boots to be dried may then be placed over the tubes in inverted position as shown 85 in Fig. 7. The heated air and gases pass upwardly into the boot and emerge from the bottom thereof carrying any moisture from within the boots with them.

In the modified form shown in Fig. 7, I 90 have shown a single tube supported by a bracket 18 which may be secured to a wall or other support 19. In this form, furthermore, I have substituted an electrical heating element 20 for the candle, a suitable 95 support 21 being provided for this electrical element which is removably secured to a socket 22 which is mounted upon the removable cap.

What I claim is:

1. A base for supporting and containing a heating device, consisting of a rectangular box-like receptacle hinged at one longitudinal edge and separable upon a diagonal plane intersecting the hinge to form two relatively movable parts; means secured to the inner surface at one of the sides which is hinged and adapted to support a heating

device; and means for locking said two receptacle parts in their open or closed position.

2. The combination of a base for supporting and containing a heating device, consisting of two hinged parts adapted when closed to form a rectangular receptacle;

means for locking said two parts in their open or closed position; and a telescopic heating tube detachably secured to one of said parts.

Signed by me this 22nd day of April, 1922.

ROBERT DEMING.
